ENCLOSED HOUSING FOR A TOY SHOOTING
GALLERY OR SIMILAR ARTICLE

Daniel Sakuta, Erie, Pa., assignor to Louis Marx & Company, Inc., New York, N. Y., a corporation of New York

Application January 10, 1955, Serial No. 33,909

Term of patent 7 years

(Cl. D34—15)

Fig. 1 is a plan view of an enclosed housing for a toy shooting gallery or similar article showing my new design;

Fig. 2 is a side elevation of the same;

Fig. 3 is an end view of the same, looking at the firing end of the range; and

Fig. 4 is an end view of the same, looking at the target end of the range.

Portions of the drawing figures are diagonally lined to indicate transparency. The dominant features of my new design are shown in solid lines in the drawing.

I claim:

The ornamental design for an enclosed housing for a toy shooting gallery or similar article, substantially as shown and described.
